HOLDER FOR CARBON PAPERS

Harry Wadsworth Wrigley, deceased, late of Manchester, England, by Sarah Ellen Wrigley executrix, Withington, Manchester, England

Application September 7, 1944, Serial No. 553,042
In Great Britain February 22, 1943

1 Claim. (Cl. 282—29)

1

This invention relates to holders for use in typewriting machines and more particularly to the provision on the holder of means for holding one or more carbon sheets in assembled relationship.

It has heretofore been proposed to provide a holder for carbon sheets with its upper end folded over on itself to form a flap and provided with one or more longitudinal cuts or slits and to affix beneath said flap a downwardly projecting tab adapted to be folded over the flap and inserted in the longitudinal cuts or slits therein. It has also been proposed to provide a holder having its upper end folded over on itself with a plurality of vertically disposed slots both in the backing sheet and flap, the carbon sheets for use in said holder being also provided with a corresponding number of slots, said carbons being held in position by a flexible member adapted to be interlaced through the several slots.

The objects of this invention are, amongst others which will be obvious, to provide a more simple means for holding one or more carbon sheets in position; to economise time in assembling and dismantling a plurality of sheets; to protect the carbon sheets through minimum handling and to effect an economy in the use of carbon sheets, and to this end according to this invention it is proposed to die cut the holder or backing sheet to provide either at the top and/or side or sides one or more pairs of hanging tabs arranged to project outwardly towards the edge of the holder and to provide the carbon sheets to be used therewith with a corresponding number of slits or slots (at the top or side or sides) adapted to be hung on the tabs.

According to a modified form of this invention it is proposed to provide at the top or side or sides of the holder tabs which are directed towards or away from each other.

According to a further modification of this invention one or more inwardly directed tabs may be provided at the top and/or side or sides of the holder, in combination with the holding tabs, said inwardly directed tab or tabs being located nearer the edge of the top or side or sides than the holding tabs.

In the accompanying drawings which illustrate this invention;

Figure 1 is a view illustrating one embodiment of this invention.

Figures 2, 3 and 4, illustrate three further modifications.

Figure 5 is a view of the protective strip.

2

Figure 6 illustrates the protective strip applied to a holder with carbon sheet.

Figures 7 and 8 illustrate a modified form of holder provided with protective means formed integrally therewith, and

Figure 9 is a view illustrating a further modification.

In the embodiment of the invention illustrated in Figure 1, 1 is the holder or backing sheet provided adjacent its upper edge with two tabs 2, hereafter called the hanging tabs, produced by die stamping or in any other convenient manner, said tabs being directed upwardly and outwardly towards the top edge of the sheet thereby forming a pair of hooks upon which are threaded or supported any desired number of carbon sheets 3 furnished with slots 4 spaced apart to correspond with the spacing of the tabs 2.

If desired a similarly formed pair of outwardly directed tabs 2a may be provided down one or both sides of the holder, the carbon sheets being provided with correspondingly positioned slots 4a so that either series may be used either alone or in combination.

The holder may, as shown in Figure 1, be provided with two inwardly directed tabs 5 or 5a placed at the top or side or sides of the holder which may be used in combination with the hanging tabs 2, 2a, said inwardly directed tabs

5, 5a being located nearer the edge of the top or side or sides than the hanging tabs, said tabs being placed over the edges of the carbon sheets to assist in preventing said sheets from becoming unhooked.

When using holders of narrow width with correspondingly narrow carbons and papers, the holder may be provided with but one inwardly directed tab 5 as shown in Figure 2.

The holder or backing sheet is preferably, but not necessarily, provided with a flap 6 adapted to turn over on top of the tabs.

According to a simplified form of this invention the holder may be furnished with two tabs 7 or 7a directed towards each other said tabs being arranged adjacent the top or side edge or edges of the holder as shown in Figure 3, the carbon sheets 3 being provided with suitably disposed slots or holes 8 or 8a.

According to a modification of the above the tabs 7 or 7a may, if desired, be directed away from each other as shown in Figure 4.

As with careless handling the carbon sheets may tend to become torn at the slots 4 it is proposed to provide means for preventing this such as by the provision of a narrow strip or stout

paper or the like 10 (Figure 5) said strip being creased as at 11 and provided with slots 12 corresponding with the slots 4 in the carbon sheets. This strip 10 is first hung on to the tabs 2 the upper edge 13 being placed under the tabs 5 as shown on the right of Figure 6 and then folded over on itself to cover the tabs 2 and also the tabs 5 or if desired the upper edge 14 of the cover part may be placed under the tabs 5 as shown on the left of Figure 6.

According to the modification illustrated in Figures 7 and 8 which is devised to attain the same end as is obtained by the strip 10 but without utilising a part formed separately from the holder, the holder is furnished with hanging tabs 15 having a length approximately twice that of the tabs 2, the locking tabs 5 are the same as in the embodiment previously described. The top edge of the holder 1 is provided with a flap 6 adapted to be turned down on top of the tabs 15 and 5, said flap is furnished immediately above the elongated tabs 15 with two pairs of parallel slits 16 through which the tabs 15 are threaded after the required number of carbon sheets have been hung on the tabs 15 and locked under the tabs 5 as shown in Figure 7.

The provision of the strip 10 as also the flap 6 and interlocking tabs 15 minimise the possibility of the carbon sheets being torn at the slots 4 and further enable the top or original sheet of paper to be more correctly positioned relatively to the under sheets.

It will be appreciated that if desired, in the place of the various tabs being cut out of the holder itself, they may be formed from pieces of material stuck on or otherwise applied to the holder in the desired positions as shown, for example, in Figure 9.

The holder may be made of any suitable material such as stout paper or Celluloid, but if made of the latter the holder would not be provided with a folded over portion at its top end.

It will be understood that the number of hanging and holding or locking tabs provided on any holder will depend to some extent on the width of the holder and the carbon sheets to be used therewith.

What is claimed is:

A holder for holding carbon sheets in assembled relationship for use in typewriting machines comprising carbon sheets and a backing sheet furnished adjacent one of its edges with a plurality of outwardly projecting tabs coherent with said backing sheet along a first line parallel to and spaced from said edge and plurality of inwardly projecting tabs coherent with said backing sheet along a second line parallel to said first line and nearer to said edge, the carbon sheets to be used with said backing sheet being provided with a pair of slits having a length slightly greater than the maximum width of said outwardly projecting tabs, said slits being provided on a line parallel to the edge of said carbon sheet and spaced from said edge a distance substantially equal to the distance between said first and second lines to enable said carbons to be hung on the outwardly projecting tabs and the free edge of said carbons to be placed under the inwardly projecting tabs, and an elongated substantially rectangular strip of material having a length equal to that of said edge of the backing sheet and being hingedly integral with the latter along one of its longitudinal edges, said strip having a width slightly in excess of the distance between said first line and said edge of said backing sheet to form a flap foldable along said edge upon said tabs to conceal and protect the same.

SARAH ELLEN WRIGLEY,
Executrix of the Estate of Harry Wadsworth Wrigley, Deceased.
